UNITED STATES PATENT OFFICE

MORTEN GRINDAL, OF MOTALA VERKSTAD, SWEDEN

MEANS FOR PACKING SAND IN FOUNDRY MOLDS AND CORES

Application filed September 10, 1929, Serial No. 391,658, and in Germany October 5, 1928.

The present invention refers to an improved method of making foundry molds and cores, more particularly to the method and means whereby the sand is packed mechanically in flasks and coreboxes.

The methods now commonly used in packing the sand in the molds may be divided into three sections. For flat work with low flasks the sand is condensed by exertion of pressure only, mainly in vertical direction. If the pressure comes from above, the sand at the top of the flask is packed harder than at the bottom, and should the pressure come from below, the sand is hardest at the bottom of the mold, around the pattern. It is practically always necessary to do some of the packing by hand, when a plain squeezing machine is used.

For high molds the sand is generally packed by means of jolting. The mold carrier is raised a certain height and given a free drop, which is suddenly interrupted. The kinetic energy gathered in the sand during the fall is thus utilized to do the work. The sand at the bottom of the mold is hardest packed, as this material is also acted upon by the descending weight of the sand above.

The sand at the top of a mold which has been jolted is never hard enough for casting purposes, and the third method commonly resorted to is therefore first to jolt the mold and afterwards subject it to a hard squeeze from above. It is sometimes practised to place a heavy plate on top of the mold during jolting, whereby an extra gravity force acts on the sand.

Jolt machines are generally built for pneumatic power. Electric or belt driven machines have been patented, and the jolting has been effected by means of an eccentric body which lifts the mold carrier a short distance at rapid intervals. However, these machines have never been a success in foundries, because of the particular intermittent conditions under which molding machines have to work: Maximum effect must be obtained instantaneously and instantaneously cut off. This can generally only be done by means of the use of fluid pressure.

The present invention provides for a con-

struction whereby the molds can be completed in one single operation without any manual work whatsoever, and with the density of the sand entirely even from top to bottom even in comparatively deep molds.

The invention which is illustrated in Fig. 1, 2 and 3, utilizes a hitherto new principle in the design of molding machines. The mold carrier is acted upon by a mechanically operated hammer. The hammer may preferably be pneumatically or electrically operated, and may be of known standard design. The number of blows per second which the hammer gives against the mold carrier may be varied within any desirable limits.

The sand is packed by means of the kinetic energy of the hammer piston, which is transmitted through the mold carrier to the sand. The result is the same as when the jolting method is used, but the principles involved in the two cases are quite different. When the mold is jolted the sand at the bottom is packed hardest, because of the dynamic effect of the sand higher up in the mold. When the mold carrier is hammered, the sand grains at the bottom of the mold will jump up and meet the static inertia of the masses above, and is thereby squeezed in between the grains of the ascending particles. Due to gravity the entire molding material is, after each blow, returned to the lowest possible position where it will immediately receive a new impulse.

It is necessary in jolting not only to lift the molding material, but even the pattern, the flask and the very heavy mold carrier for each blow. Thus much power is used. It will be seen that in the case of the hammering method a very small body, the piston of the hammer, is at work, producing the desired result with but a small fraction of the power required by a jolting machine.

In order to pack the sand at the top of the mold other means than the hammering must be resorted to. In the case of the jolting machines it is, as stated previously, possible to jolt the mold first and then squeeze. With the hammering method, however, it is possible to squeeze the mold and subject the molding material to the hammering action simultaneously. The result is of the very

highest practical value. When a plain squeeze is used, the sand will "bridge" between deep parts of the pattern, or between the pattern and the walls of the flask, with the result that the sand lying below the "bridge" will not be packed. The result is that manual work for packing sand is partly used, when ordinary squeeze machines are used. Machines built after the present invention, however, have the great advantage that any tendency to "bridge" will at once be broken up by the hammering action against the material. The intensive hammering will dislodge each grain of sand from its position in relation to the neighboring grain, and they will under the force of the pressure settle after each blow in direction of the least resistance. The result is an absolute uniform mold from bottom to top. Practice has shown, that the sand can, by means of the present invention, be packed in average sized molds in 2 to 3 seconds.

In the case of large molds it is sometimes desirable to use the hammer for a second or two before pressure is applied. The hammer may even work while the sand is shovelled into the mold. It is also possible to stop the hammer any time during the squeezing action. A highly flexible method is thus provided, making the system perfectly efficient under all varying practical conditions.

The invention has the great advantage that it can be easily built into known standard types of squeeze molding machines, as shown in the illustration.

In Fig. 1 the hammer *h* is located at the bottom of the squeezing piston 1. The piston which is worked by fluid pressure submitted and exhausted through pipe 3, travels in the cylinder 2. A beam 4 is in known manner hinged to a shaft rigidly connected to the cylinder. The beam carries a squeeze plate 5 with the adjustable spindle 6. The hammer receives fluid pressure through the pipe *o*.

The hammer is operated independently of the squeeze piston and the density of the pressure applied may even be different, for instance 80 lbs. per square inch for the hammer and say 50 lbs. per inch² for the squeeze. By regulating the squeezing power it is possible to use different dimensions of flasks on the same machine and work with the same amount of squeezing power per square unit in each case, while preferably the hammer should always work at maximum capacity. The squeeze plate is adjustable, because it is desirable to work with the smallest possible distance between the flask and the plate, and different height of flasks may be used. The hammer and the squeezing piston may act simultaneously or partly so, at the will of the operator.

In Fig. 2 a machine with a stationary mold *b* is illustrated. A flask *f* with sand *g* are shown in working position. The hammer *h*

rests in the stationary frame 7 of the machine. The squeezing plate 5 with the spindle 6 is connected to the squeeze cylinder 8 located on the beam 4. The cylinder can be actuated by means of fluid pressure in known manner. The only difference in the action of the machines shown in Figs. 1 and 2 is that in the first case the mold is lifted up against the pressure plate, and in the latter the pressure plate is squeezed down against the mold. The results are identically the same, provided the powers used are the same in both machines. Practical experiments show that the mold is packed five times as fast in this way as compared with the time used for first jolting and then squeezing.

The invention can also be used in connection with hand operated molding machines, in such a way that the hammer is operated mechanically while the pressure is exerted by manual power. Fig. 3 shows the same machine as Fig. 1, substantially, but with the pressure plate 5 movable in relation to beam 4 by means of the handle 9.

A hammer device of particularly simple construction is shown. The mold carrier *b* is fitted with an extension 10 which acts as a piston inside cylinder 11. The fluid pressure to the cylinder 11 is supplied in known manner through pipe *o*. The cylinder is supported by a spring 12 resting on the bottom of piston 1. The strength of this spring is so adjusted that it holds the piston against the mold carrier but without lifting same.

The method of operating the hammering construction in this machine is as follows: The fluid pressure submitted to the cylinder presses cylinder 11 downwards, while the table *b* with flask *f* and sand *g* remains stationary. When the exhaust position is reached, the spring 12 throws the cylinder 11 against the mold carrier *b*, and thus produces the desired hammering effect. It will be seen that even the cylinder, and not only the piston, may be utilised in carrying the invention into practice. The mold may be squeezed by hand power while the hammer is in action.

The type machines described are not the only ones to which the invention is limited, while they may be considered as preferred constructions. The invention is claimed to cover any type of machines where pressure other than gravity is exerted on the mold or core simultaneously with the action of the hammer.

Having now described my invention, what I claim as new and desire to secure by Letters Patent is:

1. In a molding machine, a supporting frame, a mold carrier adjacent thereto, a piston-like extension mounted on the mold carrier, an inner cylinder enclosing the extension, a spring supporting said inner cylinder, fluid means for operating the spring and in-

- ner cylinder to produce a jolting action on the mold carrier and mold, a squeeze-plate and operating means therefor mounted on the supporting frame.
- 5 2. In a molding machine, a supporting frame, an outer stationary cylinder attached to the frame, a squeeze-piston reciprocating in the outer cylinder, a mold carrier above the squeeze-piston, an inner hammer cylinder operating within the squeeze-piston, a piston-like extension on the mold carrier operating in the hammer-cylinder, a spring within the squeeze-piston in alignment with the hammer cylinder of proper length to normally permit 10 the inner hammer cylinder to rest against the bottom of the mold carrier, and means for compressing, and releasing the spring, and lowering the hammer cylinder, in order to deliver a jolting blow on the mold carrier, a movable squeeze-plate mounted in the frame, and means for operating the squeeze-piston in order to exert pressure on the mold and mold carrier when the mold is in contact with the squeeze-plate.
- 15 3. In a molding machine, a supporting frame, a mold carrier adjacent to said frame, an integral attached piston-like extension on the mold carrier, an inner hammer cylinder enclosing the said extension, a resilient actuating means beneath the inner cylinder, fluid means for operating the inner cylinder, and resilient means to produce a jolting action on the mold carrier and mold, an adjustably operated squeeze-plate mounted on the supporting frame, in contact with said mold and designed to resist the jolting motion of the mold, when the latter is acted upon by the resilient actuating means.
- 20 4. In a molding machine, a supporting frame, an outer squeeze-cylinder attached to the frame, a hollow squeeze-piston operating within the outer cylinder, a mold carrier in contact with said cylinder, an inner and movable cylinder positioned and operating within the squeeze-piston, a piston-like extension integral with the mold carrier reciprocating within the movable cylinder, a resilient jolting means within the squeeze-piston for jolting the piston-like extension and mold carrier, of suitable length when quiescent to permit the mold carrier to rest on the top of the squeeze-piston, fluid means for actuating the jolting means and movable cylinder, for delivering a series of hammer-like blows on the mold carrier, and adjustable pressure resisting means for resisting the action of the jolting means and the squeeze-piston, when the mold is in proximate relation with the pressure resisting means.
- 25 0 In witness whereof I have hereunto signed my name.

MORTEN GRINDAL.
